TRACK RINGS FOR RADIAL PISTON HYDRAULIC PUMPS AND MOTORS

Zbigniew Alexander Lomnicki, Codsall, England, assignor to Boulton Paul Aircraft Limited, Codsall, England

Filed Jan. 17, 1963, Ser. No. 252,128

1 Claim. (Cl. 74—567)

The present invention relates to track rings for hydraulic pumps and motors of the radial piston type.

Pumps and motors of this type are known in which the rate of rotation and volume rate of flow are not strictly proportional, resulting in an irregular pump delivery or uneven motor torque, as the case may be, even when the pump is driven at a constant rate or the motor is supplied with liquid at constant pressure. Devices of this type are exemplified by Patents 1,477,300 and 1,526,343.

The present invention provides a track ring by means of which the volume rate of flow is uniformly proportional to the rate of rotation.

Accordingly the present invention provides a track ring for hydraulic pumps or motors of the radial piston type having five or more pistons, in which the transverse axial section of the running surface of the track ring is the locus of the end of a radial line rotating about the centre of the basic circle as defined below, the length of the line being $C+f(\Delta)$, where C is the radius of the basic circle and Δ is the angle between the radial line and the bisector of the angle subtended by the working sector as defined below, and in which $f(\Delta)$ is defined by the following conditions:

$$f(\Delta) = -R \quad \text{for } -\frac{\pi}{2} \leq \Delta \leq -\alpha$$

$$f(\Delta) = R \left(\frac{\Delta}{\alpha} + \frac{1}{\pi} \sin \frac{(\pi\Delta)}{\alpha} \right) \quad \text{for } -\alpha \leq \Delta \leq \alpha$$

$$f(\Delta) = R \quad \text{for } \alpha \leq \Delta \leq \frac{\pi}{2}$$

in which conditions R is the lift of the pistons, 2α is the angle subtended at the centre of the basic circle by the limits of the working sector, and α is defined by

$$\alpha = (n-1) \cdot \frac{\pi}{2n}$$

if n is odd, and by

$$\alpha = (n-2) \cdot \frac{\pi}{2n}$$

if n is even, where n is the number of pistons.

The cross-section of the running surface of the track ring of the present invention differs from a true circle, hereinafter called the "basic circle" by amounts which are functions of the angle " Δ " displaced by the respective point on the track ring at the centre of the basic circle.

The "dwell sector" is that sector of the basic circle between the limits of which

$$\frac{d}{d\Delta}(C+f(\Delta)) = 0$$

and the "working sector" is the sector lying outside the dwell sector.

The formulae for $f(\Delta)$ hold true for

$$-\frac{\pi}{2} \leq \Delta \leq \frac{\pi}{2}$$

i.e. over one semi-circle, and for the interval

$$\frac{\pi}{2} \text{ to } \frac{3\pi}{2}$$

i.e. for the remaining semi-circle, $f(\Delta)$ is defined as

$f(\pi-\Delta)$, thus becoming a mirror image of the function in the first semi-circle.

The formula given above refers to a pump (or a motor) with one stroke per revolution and n pistons ($n \geq 5$). Motors (or pumps) with more than one, say S strokes per revolution and n pistons have also the required property provided that either

- (a) the two integers n and S have no common factor greater than unity, or
- 10 (b) n and S are both even numbers such that $n/2$ and $S/2$ have no common factor greater than unity and $n/2$ is an odd number greater than 3.

In the case of S strokes per revolution the track rings have to be contracted into S working sectors each S times smaller than the working sector in the case of one stroke per revolution. In other words a new track ring is defined in this case, by the formula $C+g(\Delta)$ where $g(\Delta)=f(S\Delta)$ and $f(\Delta)$ is assumed to have a period of 2π . When Δ ranges from 0 to 2π , Δ/S ranges from 0 to $2\pi/S$ and, for S strokes per revolution, the same movements of the pistons relatively to the basic circle are repeated S times per revolution.

The track ring of the present invention has a contour such that the sum of the contributions of the pistons to the fluid delivery from the pump or to the motor per angular displacement is constant at each angular position.

A radial piston hydraulic pump with the present track ring will produce a constant rate of fluid flow when driven at a constant rate of rotation. The torque required to drive the pump will also be uniformly proportional to the pressure at which the fluid is delivered.

A radial piston hydraulic motor with the present track ring will produce a constant torque when supplied with fluid at a constant pressure. The volume rate of flow demanded by the motor will also be uniformly proportional to the rotational speed of the motor and vice versa for a pump.

The track ring design to produce the above features is dependent upon the number of pistons and upon the number of working sectors in one revolution of the pump or motor.

The track ring contour is derived as a function of angular position, to be added to or subtracted from the basic circle. It is dependent upon the number of pistons and upon the piston lift.

The radius of the basic circle, C , the piston lift R , and the rate of rotation control the pumping rate of the pump or the torque of the motor. If this can be achieved by a piston lift, R , over a working sector of one revolution, then a pump or motor with two, three, or more working sectors per revolution and the same rate of rotation will produce the same pumping rate or torque, provided the piston lift is reduced proportionally i.e. $R/2$, $R/3$ etc.

The aforesaid designs have the additional property of producing piston accelerations as continuous functions and consequently providing relatively smooth operation: with pumps or motors having the numbers of strokes per revolution and of pistons satisfying conditions (b) (see above) a design can be achieved in which the resultant forces form a pure couple.

The improved track ring design can further be applied to variable delivery pumps and variable torque motors. The pistons of the pump or motor are to move around the interior of a tubular surface of which each cross-section perpendicular to the axis of the pump or motor corresponds with a track ring of the shape described. The maximum piston lift R is a function of the longitudinal position of the cross-section. By longitudinal displacement of the tubular surface along the rotary axis the pump delivery or motor torque can be varied in any desired manner.

The choice of the number of pistons is determined by

the requirements of the pump or motor. The torque of a motor is given by piston area multiplied by the products of n , S and R and thus, for a given output torque, these items may be varied as desired provided that the final product is unaltered.

Of the following two tables, Table 1 gives the angles of the working sectors and the dwell corresponding to the number of pistons of a pump or motor having one working sector per revolution, and Table 2 gives the radial distances from the centre of the basic circle to the track ring of a pump or motor of which $n=5$, $R=1$ unit and $C=12$ units.

Table 1

90-----	1.000000	13.0000	11.0000

The meanings of the various terms used in the above specification will be explained with reference to the accompanying drawings, in which:

FIG. 1 is a diagram showing the basic circle and the track ring contour based thereon, and

FIG. 2 is a polar diagram of a track ring having the measurements set out in Table 2.

In FIG. 1, the basic circle 1 is shown in full lines and a rough derivation of the track ring contour 2 is shown in broken lines.

This latter consists of two lobes, one inside and one outside the basic circle. The lines 3 mark the boundaries between the working and dwell sectors.

As shown, each working sector subtends an angle of 2α at the centre of the basic circle 1, having a radius C . The distance from the centre of the basic circle to a point on a track ring contour is a $C+f(\Delta)$. The angle subtended at the centre of the basic circle by the limits of the dwell sector is 2δ .

FIG. 2 illustrates the shape of the track ring of which the measurements are set out in Table 2. This track ring is for a pump or motor having five pistons, a piston lift of one unit and a basic circle of twelve units, the working sector subtending an angle of 144° .

I claim:

A track ring to be used in combination with a radial piston machine having n pistons, said track ring having a cam surface in driving connection with each of said pistons and being shaped such that, assuming a motion of each of said pistons around the center of said track ring along a path determined by said cam surface thereof, a point passing through the central longitudinal axis of each of said pistons would trace out an arcuate path which may be considered to comprise an integral number S of identical circumferential sections, where S is the number of strokes of each of said pistons per revolution of said

25 pistons and track ring relative to each other, one half of each of said sections being a mirror image of the other half, and each of said section halves comprising three successive arcs subtending angles δ , 2α and δ respectively at the center of said track ring, the first and third of said arcs being circular arcs about said track ring center and of radius $(C-R)$ and $(C+R)$ respectively, and the second 30 of said arcs being a spiral arc of radius

$$C+R\left(\frac{\Delta}{\alpha} + \frac{1}{\pi} \sin \frac{\pi\Delta}{\alpha}\right)$$

35 about the center of said track ring, where:

C is the radius of said spiral arc at the midpoint thereof, R is the lift of said pistons and less than C ,

Δ is the angle subtended at the center of said ring by a radial line to said midpoint of said spiral arc and a second radial line to another point of said spiral arc, Δ ranging from $-\alpha$ to $+\alpha$,

n is any integer not less than 5, α has any value determined by the equation

$$40 S\alpha = (n-1) \cdot \frac{\pi}{2n}$$

when n is odd, and

$$45 S\alpha = (n-2) \cdot \frac{\pi}{2n}$$

when n is even, whereby n and S have no common factor greater than unity, and in the case that n and S are both even numbers such that $n/2$ and $S/2$ have no common factor greater than unity, $n/2$ is an odd number greater than 3.
